UNITED STATES PATENT OFFICE.

HARRY C. BURKE, OF SANTA ANA, CALIFORNIA.

CLOCKING DEVICE FOR DETAIL-STRIPS.

1,393,342.

Specification of Letters Patent.

Patented Oct. 11, 1921.

Application filed September 17, 1917. Serial No. 191,688.

To all whom it may concern:

Be it known that I, HARRY C. BURKE, a citizen of the United States, residing at Santa Ana, in the county of Orange, State 5 of California, have invented new and useful Improvements in Clocking Devices for Detail-Strips, of which the following is a specification.

This invention relates to improvements 10 in such devices as cash registers; and it is an object of this invention to provide an attachment for a cash register to prevent salesmen from "beating" the register.

The difficulty which this invention is 15 designed to overcome may be explained as follows: Especially in business houses where numerous small sales are made, it is very easy for the salesman, if he takes the customers' money and operates the register, to 20 take out money for himself; and the temptation to do so is very great on account of the ease of taking out money. For instance, at a soda fountain or bar the salesman can serve a number of parties, wait until all of 25 the parties have laid down their money before taking it up, and then ring up all the sales in quick succession, registering a deficient amount for one or more of the first purchases he rings up, and registering the 30 correct amount for the last one rung up; so that the cash register will finally indicate a correct amount for one of the purchases. The salesman can do this without being detected; and, where he makes a considerable 35 amount of sales in a day, he can keep out for himself an amount perhaps equal to his day's wage without the shortage being noticed.

It is an object of this invention to over- 40 come these difficulties and to make it very difficult for a salesman to carry on such a practice without being detected.

In accomplishing this object, I provide a 45 device which will automatically mark upon the detail strip of a cash register, at periodic intervals, the time of day. By such a means I divide the detail strip into small periods, say of fifteen minutes each. In order to detect a dishonest salesman, it is then only necessary to keep a watch upon his business 50

during some one or more fifteen minute periods unknown to the salesman. The proprietor or manager can easily keep track of the business done by the salesman (by counting the number of customers served) 55 during a fifteen minute period, and then, by inspection of the detail strip for that period, he can determine whether or not the salesman has rung up the proper amount on the cash register. The salesman of course does 60 not know during what fifteen minute period he may be watched; and if my device and system are explained to a salesman when he is employed it will make him understand that he cannot cheat his employer—will make him morally afraid to do so. 65

The invention, and its use, will be best understood by reference to the following specification wherein I explain in detail a 70 preferred form of my device, reference being had to the accompanying drawings, in which—

Figure 1 is a vertical section showing a typical form of cash register mechanism and 75 its detail strip, this section being taken as indicated by line 1—1 on Fig. 3; Fig. 2 is another similar section taken as indicated by line 2—2 on Fig. 3, showing a part of my attached mechanism, Fig. 3 is a section 80 taken as indicated by line 3—3 on Fig. 2, and Fig. 4 is a face view of the clock which I employ.

In the drawings the numeral 10 designates the detail strip of a cash register. This detail strip passes from roll 11 to roll 12 over a platen 13, striker 13' and under the printing wheels 14, 15, 16, 17, etc., of the register mechanism. These printing wheels may be of the ordinary kind; wheels 16 and 17 may 85 be adapted to register the amount purchased in dollars and cents; wheel 14 may be adapted to register the number or initial of the salesman; and wheel 15 may be a numbering wheel adapted preferably, in my invention, 90 to register the number of persons in the party to whom the sale was made. This wheel 15 is particularly adapted to the business of soda fountains, saloons, etc. The striker 13' is moved upwardly against the 100

printing wheels by the usual cash register mechanism whenever the cash register is operated. In such mechanism it is customary to move the take-up roll 12 whenever the striker is moved to perform a printing operation. For this purpose any customary mechanism may be employed since the invention resides in the combination of the features hereinafter set forth with the usual cash register mechanism for performing the printing operation. In the drawings there is shown connected to the striker 13 an arm 14' pivotally connected at one end by means of a pin 15' to a link 16', which itself is supported upon the take-up roll shaft. The forward end of the arm 14' is in the form of a pawl to engage a ratchet 17' connected to the take-up roll. From the above description, it will be evident that upon upward movement of the striker the forward end of the arm 14' is drawn back and engages the ratchet 17' to actuate the take up roll 12 and move the strip 10. I do not make any claim to the general cash register mechanism; but only to the combination of my attachment, and the attachment itself.

For the purpose of my invention the detail strip 10 is made wider than usual so that it will also pass under two printing wheels 20 and 21. Printing wheel 20 is adapted to print the hour of the day and is mounted upon the shaft 22 of clock mechanism 23 to rotate with the hour hand 24 of the clock mechanism. The wheel 21 is adapted to print the minute periods of the day and is mounted upon the shaft 25 which carries the minute hand 26. In the platen 13, beneath the wheels 20 and 21, I mount my special striker 27 which strikes the detail strip 10 up toward the printing wheels 20 and 21, pressing the detail strip against the impression strip 28 which runs beneath all of the printing wheels. This striker 27 is automatically operated from the clock mechanism. An arm 30 projects beneath the striker 27 and is mounted upon a rock shaft 31. Rock shaft 31 projects into the clock mechanism and therein has an arm 32 mounted upon it. Arm 32 follows the periphery of a cam 33 which has two projections or teeth 34 over the edge of which the end of arm 32 drops (upwardly) at 15 minute intervals; a spring 35 being employed to pull the arm 32 upwardly. Cam 33 may be connected by gears, indicated at 36, to the shaft 25 carrying minute hand 26; the ratio between these gears in the present case being 2 to 1. At each quarter hour interval, when a minute printing character 21^a on wheel 21 is opposite the detail strip 10, then the arm 32 moves upwardly quickly over the edge of a tooth 34 and this action, through the medium of shaft 31 and arm 30,

throws striker 27 quickly upwardly so that the striker is thrown against the detail strip; causing the hour and the fifteen minute period of the day to be printed upon the detail strip. In order to move the detail strip at least one space between consecutive time markings (to prevent consecutive markings being made over each other, if no sales have been made during the fifteen minute interval) the roll 12 may be moved forward a space each time the arm 30 moves. This movement may preferably take place just previous to the striking movement of striker 27, and may be caused by the arm 32 moving down when a tooth 34 presses it down just previous to the upward movement of the arm. The roll 12 may have a ratchet 40 and a pawl 41 may engage the wheel and be operated by a connecting arm 42 connected with the striker arm 30.

It will be seen that with my attachment the detail strip, upon which all of the purchases are recorded, is marked so as to be divided into short time periods. This division into short time periods makes it practically impossible or at least very difficult and dangerous for a salesman to attempt taking out money for himself; because the salesman cannot know during what fifteen minute period his transactions may be watched; and because it is comparatively easy for the proprietor or manager to watch the transactions for fifteen minutes, where it is impractical for him to watch those transactions during the whole day. The recording of the number of customers also forms a check on the salesman's business; in some businesses the manager needs only to count the number of customers to know approximately how much cash the salesman has received.

Having described a preferred form of my invention, I claim:

1. In combination with a cash register mechanism having a detail strip, means for printing thereon, and means whereby said detail strip may be advanced by operation of the cash register mechanism so that successive printings thereon are distributed along its length; means for automatically marking the time of day upon the detail strip, and means coöperating with the time marking mechanism to advance the detail strip at each time printing, said last mentioned advancing mechanism being operable independently of said cash register mechanism.

2. In combination with a cash register mechanism having a detail strip, means for printing thereon, and means whereby said detail strip may be advanced by operation of the cash register mechanism so that successive printings thereon are distributed

along its length; time printing members arranged in proximity to the detail strip, a clock mechanism operating said members, means controlled by the clock mechanism for causing impressions of the time printing members on the detail strip at periodic intervals, and means controlled by the clock mechanism and operating independently of the cash register mechanism for advancing

the detail strip at each time printing impression.

In witness that I claim the foregoing I have hereunto subscribed my name this 5th day of September, 1917.

HARRY C. BURKE.
